CLAIM

The ornamental design for a flashlight body portion, as shown and described.

DESCRIPTION

FIG. 1 is a left side elevation view of a flashlight body portion showing my new design, the right side elevation view being a mirror image;

FIG. 2 is a cross-sectional outline thereof, taken along the line 2–2 of FIG. 1 and viewed in the direction of the appended arrows, showing the generally triangular design of the flashlight body portion profile with arcuate corners generally along a common circle;

FIG. 3 is a top plan view thereof; and,

FIG. 4 is a bottom plan view thereof.

The dashed lines in FIGS. 1, 3 and 4 are shown for illustrative purposes and form no part of the claimed design.
